UNITED STATES PATENT OFFICE.

HERMAN A. POPPENHUSEN, OF HAMMOND, INDIANA, AND ARTHUR P. STRONG, OF CHICAGO, ILLINOIS, ASSIGNORS TO GREEN ENGINEERING COMPANY, OF EAST CHICAGO, INDIANA, A CORPORATION OF ILLINOIS.

NOZZLE AND NOZZLE-FITTING.

1,384,086.

Specification of Letters Patent. Patented July 12, 1921.

Application filed August 22, 1919. Serial No. 319,110.

To all whom it may concern:

Be it known that we, HERMAN A. POPPENHUSEN, a citizen of the United States, residing at Hammond, in the county of Lake and State of Indiana, and ARTHUR P. STRONG, a citizen of the United States, residing at Chicago, in the county of Cook and State of Illinois, have invented new and useful Improvements in Nozzles and Nozzle-Fittings, 10 of which the following is a specification.

This invention relates to a nozzle and a fitting therefor for conduits of ash conveying or like systems.

Among the objects of our invention is to 15 provide a fitting whereby the nozzle may be readily and easily reached from the exterior of the pipe section to which it is applied, so that the nozzle when worn may be removed and be replaced by a new one from the exterior 20 of the pipe section and without being required to disconnect or otherwise disturb the connection of the steam supply pipes to the nozzle or the fitting. A further object of our invention is to provide a structure 25 whereby, when the throat of the nozzle is worn through by the steam, the steam discharged from the nozzle at its throat will be allowed to escape to the atmosphere on the outside of the pipe section through the fitting, and thus give visible signal on the outside 30 of the pipe section that the nozzle has been worn through and needs replacement by a new one. Other and further objects of our invention will appear from the following 35 specification, taken in connection with the accompanying drawings, in which—

Figure 1 is a side elevational view of an elbow section of a conduit of an ash conveying or like system and having applied thereto a nozzle and a fitting therefor constructed in accordance with our invention;

Fig. 2 is an enlarged longitudinal, vertical sectional view of said nozzle and fitting;

Fig. 3 is a transverse vertical sectional view taken on line 3—3 of Fig. 2; and

Fig. 4 is a perspective view of the nozzle removed from the fitting.

In the drawings, we have shown a nozzle and a fitting therefor constructed in accordance with our invention and applied to an elbow section 1 of a conduit of an ash conveying or like system. Said fitting comprises a bracket 2, made integral with or otherwise secured to the outer casing 3 of the

pipe section 1 and located on the outside 55 thereof. The bracket 2 is somewhat U-shaped in form and has a longitudinal web 4 spaced outward from and arranged substantially parallel to the portion of the outer casing 3 to which the bracket is secured, the web 4 60 being connected with and spaced outward from the casing 3 by webs 5, 5 at the ends thereof. The bracket is open at its side, as shown in Figs. 1 and 3, so that access may be readily had into the space between the 65 bracket 2 and the outer casing 3 for the purpose of reaching the nozzle therein and for another purpose to be hereinafter mentioned. The web 4 is provided between its ends with a threaded hole 6 opening into the 70 space between the bracket and the pipe section and in direct alignment with a threaded hole 7 in the outer casing 3 of said pipe section. Screwed into said hole 6 is a tubular member 8 having external screw threads 75 throughout its length and open at both ends and provided at its upper or outer end with a flange 9, hexagonal in shape to receive a wrench or other tool for turning said tubular member. Secured to the outside of the web 80 4 in line with the hole 6 is a pipe section 10 having a flange 11 bearing against said web and secured thereto by screw bolts 12. A pipe section 13 is connected with the one 10 by a coupling member 14, said pipe constituting a portion of the conduit by which 85 steam is supplied to the nozzle 15.

The nozzle 15 is interposed between the tubular member 8 and the hole 7, and is provided with a threaded lower end 16 to be 90 screwed into the threaded upper end of the tubular member 8. Adjacent such end, the nozzle 15 is provided with an outwardly extending flange 17 to seat against the upper end of the tubular member 8 and hexagonal 95 in shape to receive a wrench or other tool. The nozzle 15 has the shape shown in the drawings, is made of sheet metal, and has a uniform thickness throughout so that the weight and cost of construction of the nozzle 100 is reduced to the minimum. Said nozzle is provided adjacent its lower end with a restricted throat 18, and its upper end is flared outward and provided with an outwardly extending flange 19 having a circular outer edge to bear laterally against an annular wall 20 provided between the ends 105 of the passage in a tubular member 21.

screwed into the hole 7 from the outside of the pipe section 1. Said member 21 is provided at its outer end with a flange 22, also hexagonal in shape and serving to limit the distance that the member extends into the pipe section 1. In the particular form of elbow section shown, there is a liner section 23 located in the same and resting against the outer casing 3 and provided with an opening or hole 24 to receive the upper end of the tubular member 21 and permits steam to be injected into the elbow section from the nozzle 15 in the direction of flow of the ash or other material therethrough.

15. When the nozzle 15 is in position for injecting steam into the elbow or pipe section 1, the parts occupy the positions shown in Fig. 2, and it will be noted that the tubular member 8 supports the nozzle 15 with its flange 19 bearing against the wall 20 of the member 21. As the nozzle 15 is made of sheet metal and therefore has a relatively thin wall and will expand when heated by the steam passing therethrough, the upper flange 19 will engage tightly against the wall 20 to form a steam-tight joint between the parts. The wearing action of the steam passing through the nozzle is greatest on the nozzle at its throat 18, and it is at such part that the nozzle is first worn through. As the throat of the nozzle is in the space between the web 4 and the outer casing 3, the steam discharged from the nozzle through its worn throat escapes to the atmosphere on the outside of the pipe section through the open sides of the bracket 2. As the steam escapes in clouds, it can be readily seen by workmen about the system and thus gives visible signal from the exterior of the pipe section that the nozzle has been worn through and needs to be removed and replaced by a new one. When this happens the steam supply is turned off and access gained to the nozzle through the open sides of the bracket 2. The lock-nut 25, which is also hexagonal, is first loosened from its bearing against the web 4, and then a wrench or other tool is engaged about the flange 9 of the tubular member 8 and the latter screwed down toward the web 4 until the upper end of the nozzle 15 clears the tubular member 21, as shown in Fig. 3. When the parts are in such position, a wrench or other tool is engaged with the nozzle at its base flange 17 and the nozzle unscrewed from the tubular member 8 and removed from the fitting through either one of the open sides of the bracket 2. After the worn nozzle has been removed, it may 45 be replaced by a new one while the tubular member 8 is in its lowered position, as shown in Fig. 3, and when the new nozzle is engaged therewith, the tubular member 8 may be elevated to a position to engage the nozzle with the member 21 and the member 8

prevented from further movement by the clamping of the lock-nut 25 against the web 4 of the bracket. When the tubular member 8 is screwed down to release the nozzle, it extends down into the pipe sections 10 and 13 and permits the nozzle to be removed therefrom without disturbing or otherwise disconnecting the said pipe sections from the bracket 2. Thus considerable labor is avoided in removing and applying the nozzle to the fitting, and the steam pipes to the nozzle need not be disturbed or their connection with the bracket 2 be affected. Therefore, no more labor is required than that necessary to screw down the tubular member 8 and unscrew the worn nozzle therefrom and replace it by a new one. Moreover, the nozzle being made of sheet metal, the amount of material therein is reduced to the minimum, thereby not only reducing the weight of the nozzle but reducing the cost of replacing a worn nozzle by a new one.

While we have shown and described herein in detail a nozzle and a fitting therefor embodying the features of our invention, the details of construction and arrangement of parts may be variously changed and modified without departing from the spirit and scope of our invention.

We claim as our invention:

1. The combination with a pipe section, of a nozzle applied to said pipe section on the outside thereof and having its discharge end opening into said pipe section through a hole in the outer casing of the same, a fluid supply conduit for said nozzle, means connecting said conduit with said pipe section, and means establishing communication between said nozzle and said conduit and connected with said first mentioned means in a manner permitting said nozzle to be reached from the outside of said pipe section and be removed therefrom without disconnecting said conduit from said pipe section.

2. The combination with a pipe section, of an open bracket connected therewith on the outside of the same and having a web spaced outward from said pipe section, a nozzle between said web and pipe section and having its discharge end opening into said pipe section through a hole in the outer casing thereof, a fluid supply conduit on the outside of said bracket and connected with the web thereof, and a tubular member detachably connected with the outer end of said nozzle and interposed between the same and the adjacent end of said conduit and connecting the nozzle to said web.

3. The combination with a pipe section, of an open bracket connected therewith on the outside of the same and having a web spaced outward from said pipe section, a nozzle inserted into the space between said web and pipe section and having its dis-

- charge end opening into the latter through a hole in the outer casing thereof, a fluid supply conduit for said nozzle connected with said web, and a tubular member connected 5 at one end with said nozzle and opening at the other end into said conduit through said web and having screw-threaded connection with said web for permitting the nozzle to be moved with said member clear of said 10 pipe section and be removed from said bracket from the outside of said pipe section.
4. The combination with a pipe section, of an open bracket connected therewith on 15 the outside of the same and having a web spaced outward from said pipe section, a member extending through the outer casing of said pipe section opposite said web and having a passage therethrough, a nozzle inserted into said bracket between said web and said pipe section and having its discharge end opening into said pipe section through said member and bearing edgewise against the wall of the passage there- 20 through, a fluid supply conduit for said nozzle connected with said web, and a tubular member connected at one end with said nozzle and opening at its other end into said conduit through said web and having screw- 25 threaded connection with said web for permitting the nozzle to be moved with said tubular member clear of said pipe section and be removed from said bracket from the exterior of said pipe section.
- 30 5. The combination with a pipe section, of an open bracket connected therewith on the outside of the same and having a web spaced outward from said pipe section, a member extending through the outer casing 35 of the pipe section opposite said web and having a passage therethrough, a nozzle made of sheet metal and inserted into the bracket between said web and said pipe section and having a laterally projecting flange 40 at its discharge end bearing edgewise against the passage through said member, a fluid conduit for said nozzle connected with said web, and a tubular member having screw-threaded connection at one end with 45 said nozzle and opening through said web into said conduit and having screw-threaded connection with said web for permitting the nozzle to be moved with said tubular member clear of said pipe section and to be 50 removed from said bracket from the exterior of said pipe section.
- 55 6. The combination with a pipe section, of a nozzle support outside of said pipe section, a nozzle discharging into said pipe 60 section and located between the same and said support, the outer end of said nozzle terminating inside of said support, and means releasably connecting the outer end of said nozzle to said support.
7. The combination with a pipe section, 65 of an open bracket secured to and projecting outward from said pipe section, a nozzle discharging into the pipe section and located in the space between the same and said bracket, the outer end of the nozzle terminating short of said bracket, and means releasably connecting the outer end of said nozzle with said bracket.
8. A nozzle comprising a tubular outer wall made of sheet metal of a substantially 70 uniform thickness throughout the length of the nozzle and providing an axially straight passage through the nozzle, said wall being tapered inward from both ends of the nozzle to a point intermediate the 75 ends thereof to restrict the area of said straight passage at that point and thereby provide the nozzle with a contracted throat portion, said nozzle being provided at one end with an outwardly ex- 80 tending flange whereby the nozzle may be clamped to a support.
- 85 9. The combination with a pipe section having an outer casing provided with a nozzle receiving opening, of an open bracket se- 90 cured to said outer casing adjacent said opening and projecting outward from said pipe section, and a nozzle located in the space between said pipe section and said bracket and having its discharge end in said 95 opening, the discharge end of said nozzle being provided with an outwardly project- 100 ing flange bearing edgewise against the wall of said opening, the other end of said nozzle being releasably connected with said bracket.
10. The combination with a pipe section, of an open bracket secured to said pipe section on the outside thereof and having a web spaced outward from said pipe section, 105 a nozzle between said web and pipe section and discharging into the latter, said nozzle having a length less than the distance between said web and pipe section, and means connecting said nozzle with said web in a 110 manner permitting the nozzle to be moved clear of said pipe and be removed from said bracket from the outside of the pipe section.
- 115 In testimony that we claim the foregoing as our invention, we affix our signatures, this 19th day of August, A. D. 1919.
